United States Patent Office

Des. 214,473
Patented June 17, 1969

214,473

CONVERTIBLE DISPLAY STAND

John A. Plessinger, Montgomery County, Ohio, assignor to Fiberglass of Ohio, Inc., Dayton, Ohio, a corporation of Ohio

Filed Sept. 18, 1967, Ser. No. 8,641

Term of patent 14 years

Int. Cl. D6—01

U.S. Cl. D80—9

FIG. 1.

FIG. 2.

FIG. 4.

FIG. 3.

I claim:

The ornamental design for a convertible display stand, as shown and described.
